UNITED STATES PATENT OFFICE

JOHN B. DAVIDS, OF NEW YORK, N. Y.

DESIGN FOR MUCILAGE-BOTTLE.

Specification forming part of Design No. **11,476**, dated October 28, 1879; application filed September 17, 1879.
[Term of patent 14 years.]

To all whom it may concern:

Be it known that I, JOHN B. DAVIDS, of New York city, in the State of New York, have invented and produced a new and original Design for Mucilage-Holders, of which the following is a specification.

The accompanying drawings form a part of this specification.

In the drawings, Figure 1 is a side elevation, showing the holder with a fountain-brush inserted, as it will appear in a state of rest when ready for use on a desk. Fig. 2 is a plan view of the holder alone, and Fig. 3 is a rear view of the latter.

Similar letters of reference indicate like parts in all the figures.

A is the main reservoir. It is of an ovoidal or flattened spheroidal form, with an extension on one side, to or on which is connected the mouth B, which is formed as shown, and surmounts a generally cylindrical well (marked C) slightly ornamented with beads c, as shown. The side of the body opposite the well C presents a hollow, a, which diminishes across under the bottom, as shown.

The body overhangs the base at each side, and also at the back or side opposite to the well. A gracefully-rounded groove or inden-

tation extends along each side a little above the base, as indicated at a'.

I have shown in one figure a fountain-brush. In that M is the bulb, m the neck, and N the collar, having a deep lip, N'. It appears as a continuation surmounting the well C.

I claim—

1. The design for a mucilage-holder herein shown and described, the same consisting in the body A, of flattened spheroidal form, overhanging the base, with the side grooves, a', and the bottom hollow, a.

2. The design for a mucilage-holder herein shown and described, the same consisting of the cylindrical well C, formed with beads c, joined to the body A, of flattened rounded form.

3. The design for a mucilage-holder herein shown and described, the same consisting of the flattened rounded reservoir A, with the bottom hollow, a, and side grooves, a', and of the generally cylindrical well C, rising higher than the body A, and presenting the beads c.

JOHN B. DAVIDS.
